ABSTRACT

A money container setting circuit in an automatic money dispenser operated to dispense money of a plurality of monetary denominations, which circuit comprises: a section storing the denominations of money to be dispensed and producing signals for storing the denominations of the money; a section commanding the start of money dispensation and producing a signal for starting the dispensation of money; and a container-position detecting section producing coincidence signals when a money container is coincidentally set at money-dispensing positions thereof, whereby the money container is controlled by these signals.

MONEY CONTAINER SETTING CIRCUIT IN AN AUTOMATIC MONEY DISPENSER

CROSS REFERENCE TO RELATED APPLICATIONS

This application is a continuation-in-part of application Ser. No. 299,402, filed Oct. 20, 1972 now abandoned.

BACKGROUND OF THE INVENTION

The invention relates to automatic money dispensers and more particularly to a circuit for setting a container section containing money (hereinafter referred to as a money-container setting circuit) in the automatic money dispenser.

Known in the art as an automatic money dispenser comprising a money container having a plurality of frames each containing money of one denomination only, for instance a first frame containing 10,000-yen bank notes only, a second frame containing 1,000-yen bank notes only, and so forth. In this conventional money dispenser, when a particular monetary denomination is designated by means of a function key, the position of the money-containing frame corresponding to the monetary denomination thus designated is set at a money-dispensing position predetermined in relation with a money-dispensing section, and thereafter the money of the denomination designated by the function key is dispensed through a money-dispensing outlet by the operation of the money-dispensing section.

However, conventional automatic money dispensers such as described above suffer from the disadvantage that the money container is sometimes set or money having an undesirable or incorrect denomination.

SUMMARY OF THE INVENTION

A first object of the invention is to provide a money-container setting circuit of an automatic money dispenser which eliminates the disadvantages accompanying conventional automatic money dispensers during the setting operation of its money container.

A second object of the invention is to provide a money-container setting circuit in an automatic money dispenser which can set a money container correctly with respect to each monetary denomination specified, whereby the reliability of the automatic money dispenser is much improved.

A third object of the present invention is to provide a money-container setting circuit in an automatic dispenser which includes a circuit for designating the order of money dispensations and a manual command section adapted to selectively command the monetary denominations by a manual operation, whereby the operation of setting the money container may be carried out either automatically or manually.

The foregoing object and other objects as well as the characteristic features of the invention will become more apparent from the following detailed description with respect to a preferred embodiment of the invention when read in conjunction with the accompanying drawings.

BRIEF DESCRIPTION OF THE DRAWINGS

FIG. 1 is a schematic block diagram illustrating a preferred embodiment of an automatic money dispensing system including the money-container setting circuit according to the present invention;

FIGS. 2 and 2a are a detailed partial schematic, partial block diagram of the system of FIG. 1 according to a preferred embodiment of the present invention; and FIG. 3 is a diode matrix assembly which forms the Order Designation Section of FIG. 2a.

DETAILED DESCRIPTION OF THE INVENTION

Referring now to FIG. 1, there is shown an overall partial block, partial schematic diagram illustrative of 10 the money-container setting circuit of the present invention in an automatic money dispensing system. The money-container setting circuit includes a dispenser control section 8, a storage section 1, a drive control section 4, driving means 5, and a container-position detecting section 3. The foregoing elements are interconnected within a money dispensing system which includes a money container 9 which, for example, comprises a drum containing separate compartments for housing the individual money denominations, and a 20 money dispensing section 10 which receives money from the adjacent compartment of money container 9. By way of illustration, money container 9 is shown in FIG. 1 to include three compartments or frames which respectively house 100-yen notes, 1,000-yen notes, and 25 10,000-yen notes. Accordingly, if money container 9 is in the position as depicted in FIG. 1, the container housing the 10,000-yen notes is adjacent the money dispensing section 10 from which the 10,000-yen notes will issue. In order to obtain other denominations from 30 money dispensing section 10, money container 9 must be rotated so that the proper compartment or frame rests adjacent the money dispensing section 10.

The container position detecting section 3 is coupled to money container 9 so as to provide an indication to 35 drive control section 4 as to which of the various compartments or frames within money container 9 are adjacent the money dispensing section 10, as will become more clear hereinafter.

The initial information regarding the total amount of 40 money to be dispensed and in what denominations is provided by means of dispenser control section 8. Dispenser control section 8 provides signals to storage section 1 indicative of the denominations of money desired to be output from money dispensing section 10. Storage section 1 preferably comprises a plurality of flip-flops corresponding in number to the number of different denominations of money available to be dispensed from money container 9 and money dispensing section 10. Storage section 1 provides an output signal 45 to drive control section 4 to indicate that a particular money denomination is desired to be output from money dispensing section 10. If that particular denomination fails to correspond to the compartment or frame within money container 9 which is then adjacent money dispensing section 10 as detected by container position detecting section 3, drive control section 4 activates driving means 5 to bring the proper compartment or frame within money container 9 into alignment with money dispensing section 10. Once the desired alignment between the compartment or frame of 50 money container 9 with money dispensing section 10 is achieved, drive control section 4 ceases actuation of driving means 5. The money dispensing section 10 is then actuated to dispense the desired number of bills of that denomination. The number of bills dispensed of that denomination is monitored by dispenser control section 8 and, upon detecting that the desired number 55 60 65

of bills of that particular denomination have been dispensed by money dispensing section 10, dispenser control section 8 provides a reset signal to the corresponding flip-flop within storage section 1.

Thereafter and automatically, the storage section 1 in combination with the drive control section 4 proceeds to distribute the desired number of bills of the next lower denomination. This process is repeated until the total amount originally indicated by dispenser control section 8 has been delivered through money dispensing section 10. In the foregoing manner, automatic distribution of the proper number of bills of each denomination is achieved. Dispenser control section 8 also includes a manual command section, to be explained in more detail hereinafter, which bypasses storage section 1 to provide a direct indication of the desired denomination to drive control section 4.

Referring now to FIG. 2, there is illustrated a detailed schematic diagram of the money dispensing system embodying the present invention. The dispenser control section 8 is seen to comprise a money-amount input means 20, a function key 22 which includes a plurality of keys corresponding to the different denominations of money to be distributed, a storage/count circuit section 24, a manual command section 7, and a dispensation-start commanding section 2.

The instruction input, i.e., the data regarding the desired monetary denominations and money therefor, are delivered by means of the money-amount input means 20 and the function key 22. One money amount is designated by money-amount input means 20 for one denomination selected by function key 22. For example, 20,000 yen may be designated by money-amount input means 20 and the 10,000-yen key of function key 22 may be designated for the dispensation of 10,000-yen notes. If the 20,000 yen designated by money-amount input means 20 is desired in 1,000-yen notes, the 1,000-yen key of function key 22 is designated. This data regarding the monetary denominations and the money amounts therefor are delivered from money-amount input means 20 and function key 22 to a storage/count circuit section 24, which comprises a storage circuit for storing the data on the money amount designated to be dispensed, and on count circuit which counts the number of pieces of money dispensed from the money dispensing section 10 by means of a photoelectric type money detector provided in the money conveying path of the money dispensing section 10 and which when a money amount represented by the number in pieces of money dispensed coincides with the money amount represented by the data stored in the storage circuit, detects it. When the desired number of bills of a particular denomination dispensed from money dispensing section 10 corresponds with that amount previously stored in storage/count circuit section 24, the latter delivers a resetting signal to the remainder of the circuitry, as will become more clear hereinafter.

The outputs of the function key 22 of dispenser control section 8 which are indicative of the desired denominations of bills to be dispensed are fed to storage section 1. Storage section 1 comprises flip-flops FF₁, FF₂, and FF₃. The outputs from storage section 1 are fed to drive control section 4 which includes gates G₁, G₂, and G₃ whose outputs are respectively fed to flip-flops FF_{1a}, FF_{2a}, and FF_{3a}. The drive control section 4

further comprises gates G_{1a}, G_{2a}, G_{3a}, G₄, G₅, G₆, G₇, and an order designating section 6.

The operation of gates G_{1a}, G_{2a}, G_{3a}, and G₄ through G₇ are controlled with the aid of three control signals A, B and C, that is, a signal A for storing a monetary denomination, a signal B for starting the dispensation of money and a signal C for detecting the coincidence of a money-containing frame of the money container 9 with the desired money-dispensing position (hereinafter referred to as a monetary-denomination storing signal A, a dispensation-starting signal B and a coincidence-detecting signal C, respectively).

The monetary-denomination storing signal A is produced initially from storage section 1 which stores the denominations of money designated to be dispensed from the money dispenser 9, the dispensation starting signal B is produced from a section 2 for commanding the start of the money dispensation, and the coincidence-detecting signal C is produced from the container-position detecting section 3 which detects the coincidence of the position of the money-containing frame of money-container 9 corresponding to the monetary denomination designated with the desired money-dispensing position. Furthermore, the money-container setting circuit of the present invention is provided with a money-container driving section 5 which is controlled by an output from the drive control section 4.

Within drive control section 4, output flip-flops FF_{1a}, FF_{2a} and FF_{3a} are provided correspondingly to the flip-flops FF₁, FF₂ and FF₃, respectively; and AND gates G₁, G₂ and G₃ are also in correspondence with the flip-flops FF₁, FF₂ and FF₃, respectively. The outputs F of the flip-flops FF₁, FF₂ and FF₃ are applied through the gates G₁, G₂ and G₃ to the flip-flops FF_{1a}, FF_{2a} and FF_{3a}, respectively. The outputs $\bar{F}$ of the flip-flops FF₁, FF₂ and FF₃ are introduced to a circuit 6 for designating the order of money dispensations (hereinafter referred to as an order-designating circuit 6) which for example may comprise a diode matrix. This diode matrix is formed with diodes in the form of a matrix so that when a signal at a low level is obtained at the terminal F of the flipflop FF₁, this signal $\bar{F}$ is introduced to the other terminals of the AND gates G₂ and G₃, and when a signal at a low level is obtained at the terminal $\bar{F}$ of the flipflop FF₂, this signal $\bar{F}$ is introduced to the other terminal of the AND gates G₃, whereby the operations of the AND gates G₂ and G₃ and that of the AND gate G are inhibited by these signals $\bar{F}$ respectively.

Order-designating circuit 6 provides enabling inputs to gates G₁, G₂ and G₃ in the following predetermined manner. When the flip-flop FF₁ is set, an output signal of a high level is produced from the flip-flop FF₁ and order-designating section 6 thereby to open the gate G₁; when the flip-flop FF₁ is reset while the flip-flop FF₂ is set, an output signal of a high level is produced from the flip-flop FF₂ and order-designating section 6 thereby to open the gate G₂; and when both of the flip-flops FF₁ and FF₂ are reset while the flip-flop FF₃ is set, an output signal of a high level is produced from the flip-flop FF₃ and order-designating section 6 thereby to open the gate G₃.

When the gates G₁, G₂ and G₃ are thus opened, the outputs F of the flip-flops FF₁, FF₂ and FF₃ are introduced through the gates G₁, G₂ and G₃ to the flip-flops FF_{1a}, FF_{2a} and FF_{3a}, respectively. As a result, the flip-flops FF_{1a}, FF_{2a} and FF_{3a} are set, and the monetary-

denomination storing signals A are produced therefrom.

The container-position detecting section 3 comprises switches SW₁, SW₂ and SW₃ which are provided separately for each monetary denomination. In each of the switches, when the position of the money-containing frame with which the switch is associated in money-container 9 reaches or coincides with the desired money-dispensing position in correlation with the movement of the money container 9, the switch is closed thereby to produce the coincidence-detecting signal C of a high level.

The dispensation-start commanding section 2 comprises a push-button SX for starting the dispensation of money. When this push-button SX is depressed, the dispensation-starting signal B is produced from the dispensation-start commanding section 2.

The money-container driving section 5 includes a control relay RY and a switching transistor T connected to the relay RY. The relay RY controls a turret motor 26 which revolves the money container 9. When the switching transistor T becomes conductive, the relay RY is energized thereby to revolve the money container 9.

In drive control section 4, AND gates G_{1a}, G_{2a} and G_{3a} are provided in correspondence with the monetary denominations and AND gate G₄ is provided to receive an enabling signal from push-button SX. The gates G_{1a}, G_{2a} and G_{3a} receive the respective output signals A corresponding to the monetary denominations originating from the storage section 1 and also the respective output signals C from the container-position detecting section 3 to thereby produce output signals. These outputs are fed through wired OR gate G₇ to the gate G₄. When the gate G₄ receives the output signal B from the dispensation-start commanding section 2 upon depression of the push-button SX, the output of the gate G₄ is introduced through an OR gate G₆ to the switching transistor T whereby this transistor T becomes conductive.

The money-container setting circuit further comprises a manual command section 7. In this section 7, monetary denominations of "10,000", "1,000" and "100" may be selected by a manual operation to override the automatic operation of money-amount input means 20, function key 22, and order-designating section 6. As a result, command signals which will set the flip-flops FF_{1a}, FF_{2a} and FF_{3a}, respectively, are produced, while a control signal is produced to open an AND gate G₅ whose one input receives the output of the gate 7.

The setting terminals S of the flip-flops FF₁, FF₂ and FF₃ in the storage section 1 are respectively connected to input terminals T₁, T₂ and T₃ which respectively receive signals which designate the monetary denominations "10,000", "1,000" and "100" which signals are produced by function key 22. The resetting terminals R of the flip-flops FF₁, FF₂ and FF₃ are connected to input terminals EOT₁, EOT₂ and EOT₃, respectively, which receive respective resetting signals produced by storage/count circuit section 24 when the money-dispensing section 10 completes the dispensations of the money of the various denominations, as aforescribed. For instance, when the money-dispensing section 10 completes the dispensation of the proper number of 10,000-yen bills, a resetting signal is produced by section 24 and introduced through the input terminal EOT₁ to the input terminal R of the flip-flop FF₁.

In addition, the storage section 1 is provided with an input terminal R which receives a resetting signal for resetting the number of whole flip-flops FF₁, FF₂, FF₃, FF_{1a}, FF_{2a} and FF_{3a}. The terminal R may be connected to a clear command section provided separately which is manually operated to reset forcibly the flipflops FF₁, FF₂, FF₃, FF_{1a}, FF_{2a}, and FF_{3a}, or to an initial reset circuit which is provided to prevent an erroneous operation which may be caused upon energization, and which upon energization automatically operates to produce a reset signal.

The operation of the money-container setting circuit of the present invention will be described with respect to the case where, for instance, 21,300-yen is dispensed with two sheets of 10,000-yen bank notes, one sheet of a 1,000-yen bank note, and three sheets of 100-yen bank notes out of the money dispenser 10.

First of all, the signals for designating the monetary denominations "10,000", "1,000" and "100" are produced by means of the function key 22. The total amount of money to be dispensed for each denomination is designated by money-amount input means 20 whose output is stored in storage/count circuit section 24 (along with the function key 22 information) to provide a means for determining when the proper number of bills for each denomination has issued from money dispensing section 10. The outputs from function key 22 are also fed to the flip-flops FF₁, FF₂ and FF₃ which then are set, whereby the gate G₁ is opened with the aid of the order-designating circuit 6 and the flip-flop FF_{1a} is set through the gate G₁ thus opened (while the flip-flops FF_{2a} and FF_{3a} are maintained set). Therefore, an output of a high level from the flip-flop FF_{1a} is fed to the gate G_{1a}.

Under this condition, if the position of the frame of money-container 9 which contains the 10,000-yen bank notes is not in coincidence with the money-dispensing position dictated by money dispensing section 10, the switch SW₁ is kept open and an output of a high level is therefore applied from a power source Vcc to the gate G_{1a}, as a result of which an output of a high level is delivered from the gate G_{1a} to the gate G₄.

Under these conditions, upon depression of the push-button SX of the dispensation-start commanding section 2, the gate G₄ is opened, and the output of the high level from the gate G_{1a} is fed through the gate G₆ to the transistor so as to make the latter conductive, as a result turret motor 26 is activated and the money container 9 starts its revolution.

When the position of the 10,000-yen containing frame coincides with the money-dispensing position by the revolution of the money container 9, the switch SW₁ is closed, whereby a detecting signal of a low level is applied to the gate G_{1a}. As a result, the gate G_{1a} is closed and the transistor T is therefore turned off or non-conductive, so that the revolution of the money container 9 will cease. In this case, the output of the gate G_{1a} which has changed to the low level from the high level as described above, is utilized, as a brake driving signal E so as to activate a brake provided for the money container 9.

When the 10,000-yen containing frame is thus set at the proper money-dispensing position and two sheets of 10,000-yen bank notes are dispensed one by one out of the money dispenser, the latter is detected by storage/count circuit section 24 which generates a resetting sig-

nal representing the completion of the dispensation of 10,000-yen bank notes and is applied to the input terminal EOT₁. As a result, the flip-flops FF₁ and FF_{1a} are reset, while a control signal is produced from the order-designating circuit 6 to open the gate G₂, whereby the flip-flop FF_{2a} is set. At the same time, the output of the gate G_{2a} is changed from the low level to the high level, resultantly the transistor T is turned conductive so that the money container 9 starts its revolution again.

Upon start of the revolution of the money container 9, the switch SW₂ is operated in the same manner as in the case of the switch SW₁ described above, and the frame containing the 1,000-yen bank notes is set at the money-dispensing position by the revolution of the money container 9. When the proper number of 1,000-yen bank notes has been dispensed, as detected and stored in circuit 24, the latter provides a reset signal to terminal EOT₂. Then, similarly as in the cases described above, the dispensation of the 100-yen bank notes is carried out automatically until the full and proper amount has been dispensed.

The situation in which money of various monetary denomination is automatically dispensed out of the money dispenser 9 has been described above. However, if the money is desired to be dispensed manually with no predesignated order or total, the monetary denominations may be successively commanded by the manual command section 7. In this case, every time the manual command section commands a particular monetary denomination, the components corresponding to or related to the monetary denomination thus commanded are operated in the same manner as described above and the frame containing the money of the denomination thus commanded is set at the money-dispensing position.

As is apparent from the above-description, according to the present invention, the money-containing frames of the money container can be sequentially and correctly set at the money-dispensing position according to the monetary denominations, whereby the reliability of the money dispenser can be improved remarkably in its money-dispensing operation.

Furthermore, according to the present invention, the order-designating circuit 6 and the manual command section 7 are provided in the money-container setting circuit, whereby the operation for setting the money container may be carried out either automatically or manually.

The money-containing frames described above are radially arranged. However, it should be noted that the invention could be applied to a money container in which the money-containing frames are arranged vertical or horizontal.

We claim as our invention

1. A money container setting system in an automatic money dispenser having a dispenser control section to control the dispensation of money, said system comprising:

a money container having a plurality of money containing frames each containing money of a particular monetary denomination;

driving means for setting each one of said money containing frames containing money of a predetermined monetary denomination to be dispensed at a money dispensing position of said automatic money dispenser;

a money dispensing section for dispensing money out of each one of said money containing frames when set at said money dispensing position;

storage means for storing the monetary denominations of money designated to be dispensed and providing respective denomination storing signals representative thereof;

monetary denomination detecting means operatively responsive to said denomination storing signals for detecting the denomination of money contained in each one of said money containing frames when set at said money dispensing position; and

drive control means for applying a driving command signal to said driving means until the denomination of money to be dispensed, which is selected in a predetermined order of priority determined by the denominations stored in said storage means, is detected by said monetary denomination detecting means in response to respective ones of said denomination storage signals, whereby money to be dispensed is successively selected and set at said money dispensing position.

2. A system as claimed in claim 1, in which said storage means comprises a storage circuit device having a plurality of storage circuits in which monetary denominations of money to be dispensed are respectively

35 stored separately according to monetary denomination, and when a sum of money dispensed by said money dispensing section has reached a predetermined amount, dispensation completion signals are generated in the dispenser control section of said money dispenser in response thereto and applied to reset said storage circuits thereby to eliminate the contents stored therein.

3. A system as claimed in claim 1, which further comprises an order-designating circuit constituted in a matrix state, said order-designating circuit receiving input signals from said storage means respectively representative of the denominations of money stored therein and selecting said denominations one at a time in an order of priority predetermined by the combination of said denominations of money.

4. A system as claimed in claim 2, which further comprises an order-designating circuit constituted in a matrix state, said order-designating circuit receiving input signals from respective ones of said storage circuits representative of the monetary denominations stored therein and selecting said denominations one at a time in an order of priority predetermined by the combination of said denominations of money.
